COOLING SYSTEM FOR COMBUSTION ENGINES

Gustaf Waldemar Björkström, Stockholm,
SwedenApplication August 12, 1936, Serial No. 95,641
In Sweden August 17, 1935

9 Claims. (Cl. 123—170)

The invention relates to combustion engines, more particularly to a cooling system of the type in which the cooling fluid circulates through the cooling jacket of the engine and a mixing chamber which is connected to a pump supplying additional cooling fluid to be mixed with the circulating cooling liquid to cool the same, and which mixing chamber is provided with an outlet for the heat surplus cooling fluid.

Usually the engine, as for instance of a boat, is cooled by water pumped into the cooling jacket directly from the sea, the cylinder becoming cooled at the bottom to substantially the temperature of the cooling water, but in order to correspond as closely as possible to the middle cooling suitable to the combustion temperature it must obtain at the top thereof a considerably high temperature which causes heat stresses in the walls of the engine cylinder and the power of the engine.

One object of the invention is to overcome this drawback and to provide a cooling system in which the various parts of the cylinder are cooled to the correct extent at normal engine speed as well as at light running.

According to an essential feature of the invention the mixing chamber is provided with a baffle device situated between the inlet for the additional cooling fluid and the outlet for the surplus cooling fluid. Such baffle device assists in effecting a satisfactory mixing of the additional fluid and the circulating fluid and further it provides a means for separating the heat surplus fluid which is to be drawn-off from the mixing chamber or alternately be carried to a radiator for cooling purposes.

According to another feature of the invention the mixing chamber is connected to the outlet and the inlet of the cooling jacket of the engine so as to cause the cooling fluid to pass, due to the thermosiphon action, through the cooling jacket and the mixing chamber.

Due to the heat supplied from the cylinder when the cooling water is circulating at normal speed, the cooling water pumped into the cylinder is to be mixed intimately with the water escaping from the cooling jacket and thus must not form a stream which will pass unmixed through the water mass of the mixing chamber. To this end the mixing chamber according to the invention is given a suitable shape and is furnished with a nozzle having a certain area of passage and such a direction that the cooling water is injected in the shape of a jet which effects a helical motion and a mixing of the water mass partly by a

certain velocity, partly by a given direction and partly by means of guide vanes.

When the motor is operating at reduced power or is running light the power of the water pump is reduced to such a considerable extent that where no particular steps were taken the water flow would not be in proportion to the heat supply from the engine cylinder and therefore the engine would become too hot. At a low number of revolutions the flow through the nozzle will be reduced to an immaterial jet which is naturalized immediately in the water mass. The fact that the hot water tends to ascend and the cooled water to descend is utilized in the present invention in such a manner that the mixing chamber is formed with a channel, at which the pipe to the cooling jacket begins and which is given such a position that the weak cold water flow from the nozzle is kept separated from the remainder of the water in the mixing chamber, follows the natural circulation in this channel and cools in this way directly the water supply to the cooling jacket, whereby the engine cylinder obtains the cooling required to maintain the engine at a suitable temperature, even when the engine operates at reduced power and at a low number of revolutions. For the control of the cooling water quantity from the pump a cock is suitably arranged to control the flowing-in quantity of the additional water to be mixed with the circulating cooling liquid.

The invention is illustrated in the accompanying drawing which shows an embodiment of the cooling system. Fig. 1 is a side elevation of an engine provided with a mixing chamber. Fig. 2 is an end view of the same arrangement as that shown in Fig. 1 but having the cover of the mixing chamber removed. Fig. 3 is a section after lines A—A in Fig. 2 and B—B in Fig. 7, showing an assemblage of the mixing chamber. Fig. 4 shows a detail of the cover of the mixing chamber, shown in a top view as compared with Fig. 3. Fig. 5 shows the cover of the mixing chamber in the same position as that shown in Fig. 4 but looking towards the front thereof. Fig. 6 is a section on line C—C of Fig. 7 showing a detail of the cover of the mixing chamber and an embodiment of a tubular baffle arranged adjustably and surrounded by a helical guide vane. Fig. 7 is a top view of the same arrangement as that shown in Fig. 6. Fig. 8 is a sectional view on line D—D in Fig. 6 showing the tubular baffle device as seen from the front thereof. Fig. 9 is a section through the mixing chamber along E—E in Fig. 1 on an enlarged scale.

The drawing illustrates an embodiment, in which the outlet of the engine cylinder 1 for the cooling water coming from the jacket is connected by a chamber 2A and a flange 2 to the mixing chamber 3A, 6 having a cover 4. The chamber 3A, 6 is shaped in the present case as a horizontal cylinder the axis of which is directed to the flow direction of the water coming from the engine jacket and for mixing the cooling water is provided with a baffle 5 separating a chamber 6 which is connected by a channel 7 with the pipe 8 for the cooling water outlet and further with the channel 9 which is suitably positioned at one end of the cylindric portion. Said channel 9 is arranged so as to easily receive water in the direction of flow or a direction being tangential to the direction of flow of the water in the mixing chamber 3. The passage 9 is connected by a pipe 10 to the inlet of the cylinder jacket. The cylinder 3A is furnished at the end opposite to the passage 9 with a nozzle 11 provided tangentially in relation to the wall of the cylinder 3A and connected by a pipe 12 with an adjusting cock 13 having a lever 13A and connected also to the water pump 14 which is driven in the present case from the crank shaft of the engine. The nozzle is provided with an outlet 11A having a passage area suited for a water jet. The pump 14 is connected to a suction pipe 15 and control cock 13 with an outlet pipe 16. In the present case the cover 4 is positioned adjacent to the nozzle 11 for the cooling water supply and furnished with a helically shaped surface 17 disposed in the direction of the water jet from the nozzle 11 and adapted as a guide for the water flow; said surface terminates at 18 in a surface 19 suitably arranged at right angles to the cover 4. Furthermore, the cover 4 comprises a tubular baffle 20 in the present case being adjustable 40 relatively to the cover 4 by a bolt 20A and a nut 20B and having its axis directed in the same sense as the axis of the cylinder 3A; the baffle has such a position that a portion of the water from the cylinder jacket 1 flows into its inlet opening. At the end opposite to the inlet the baffle 20 is provided in the present case with a passage 21 which is disposed adjacent to the guide surface 17, 18 of the cover 4. Furthermore, the baffle 20 is provided at the outer wall thereof with 50 a helical guide vane 22. The baffle wall 5 is suitably provided with a passage 23 to discharge the air or possible steam blisters escaping from the mixing chamber 3A. In the present case the chamber 2A disposed above the engine cylinder 55 is formed with a suitable shape and a sufficient height and passage area to effect the separation of the superheated water which is to be separated from the colder portion of the water mass.

As shown in the drawing the cooling water circulates in the direction of the arrow. The water escaping from the cooling jacket of the cylinder 1 is divided in the chamber 2A into superheated and colder water the former flowing as shown by the arrow 24 above the baffle 5 and the latter as 60 shown by the arrows 25 and 25A below the baffle 5. The portion of the water separated above the baffle 5 is mixed to a great extent with steam blisters and is discharged through the outlet 7, 8. The water below the baffle 5 is mixed in the mixing cylinder 3A with the water jet and is imparted circulation thereby in the direction of the arrow 26 from the nozzle 11 which is connected by the pipe 12 and the cock 13 to the pump 14 and the suction pipe 15, and which continues as 70 shown by the arrow 28 through the channel 9

and the pipe 10 back to the cooling jacket of the cylinder 1. The water from the nozzle 11 is caused to move in a helical path partly by the disposition of the tubular baffle 20 in the mixing chamber and partly by the helical guide surface 17, 18 of the cover 4 and the helical guide vane 22 of the baffle 20 so that the water obtains a motion as shown by the arrows 27, 27A, 27B. The water obtaining the direction of flow as shown by the arrows 25A and passing through the baffle 20 continues, due to the suction effect of the circulation behind the surface 19 of the cover 4, through the passage 21 and is associated with the water escaping from the nozzle 11. By turning and the baffle 20 being rotatable in relation to 15 the cover 4 and provided with a stop device and formed in the present case as a tube having a base, and the passage 21 beneath the projection arranged at the cover 4 for the guide surface 17, 18, in the direction against the surface 19, the 20 area of the passage 21 may be adjustably controlled for the circulating water quantity from the cylinder jacket. The additional water quantity needed for the cooling is controlled by shifting the lever 13A of the cock 13, and surplus 25 water delivered from the pump is discharged through the tube 16. When the engine is running at a low number of revolutions the water jet through the nozzle 11 is reduced to an essential degree so that the helical motion of the water 30 mass will almost cease in the mixing chamber. The cooled water running in will then follow the bottom of the mixing chamber as, shown by the arrow 29, follows the path of the thermosiphon circulation through the channel 9 of the mixing 35 chamber, and continues together with the portion of the water from the cylinder jacket through the tube 10 to the cooling jacket of the cylinder.

Without departing from the spirit of the invention the mixing chamber may have another constructional form than that shown or the arrangement be constructed with a specially shaped chamber for separating the superheated water, or provided with more or less complicated baffle system departing from the drawing. 45

What I claim is:—

1. In a cooling system for combustion engines comprising a cooling jacket and a mixing chamber for circulating cooling fluid and a pump for supply of additional cooling fluid to be mixed with the circulating cooling fluid, the combination of an outlet in the upper part of said mixing chamber for surplus cooling fluid, an inlet in said mixing chamber for the additional cooling fluid, a communication for mixed cooling water between the mixing chamber and the lower portion of the cylinder jacket and baffle means in said mixing chamber situated between said outlet and said inlet to separate the most heated part of the circulating cooling fluid from said cylinder cooling 60 jacket.

2. In a cooling system for combustion engines comprising a cylinder cooling jacket and a mixing chamber for circulating cooling fluid and a pump for supply of additional cooling fluid to be mixed with the circulating cooling fluid, the combination of an outlet in the upper part of said mixing chamber for surplus cooling fluid, an inlet in said mixing chamber for the additional cooling fluid, arched baffle means in said mixing chamber situated between said outlet and said inlet to separate the most heated part of the circulating cooling fluid and a communication for mixed cooling water between the mixing chamber and the lower portion of the cylinder jacket. 70

3. In a cooling system for combustion engines comprising a cylinder cooling jacket and a mixing chamber for circulating cooling fluid and a pump for supply of additional cooling fluid to be mixed with the circulating cooling fluid, the combination of an outlet in the upper part of said mixing chamber for surplus cooling fluid, an inlet in said mixing chamber for the additional cooling fluid, baffle means in said mixing chamber situated between said outlet and said inlet, to separate the most heated part of the circulating cooling fluid, a space above said baffle means, a space below said baffle means, and a passage connecting said spaces.
4. In a cooling system for combustion engines comprising a cylinder cooling jacket and a mixing chamber for circulating cooling fluid and a pump for supply of additional cooling fluid to be mixed with the circulating cooling fluid, the combination of an outlet from said mixing chamber for surplus cooling fluid, an inlet in said mixing chamber for the additional cooling fluid, baffle means in said mixing chamber situated between said outlet and said inlet, a tubular chamber disposed below said baffle means, said inlet for the additional cooling fluid being tangential to the wall of said tubular chamber.
5. In a cooling system for combustion engines comprising a cylinder cooling jacket and a mixing chamber for circulating cooling fluid and a pump for supply of additional cooling fluid to be mixed with the circulating cooling fluid, the combination of an outlet from said mixing chamber for surplus cooling fluid, an inlet in said mixing chamber for the additional cooling fluid, baffle means in said mixing chamber situated between said outlet and said inlet, a tubular chamber disposed below said baffle means, an end of said tubular chamber arranged with an opening adjacent to said cylinder cooling jacket, said inlet for the additional cooling fluid being tangential to the wall of said tubular chamber, a helical guide surface disposed at one end of said tubular chamber adjacent to said tangential inlet and associated with an axial surface.
6. In a cooling system for combustion engines comprising a cylinder cooling jacket and a mixing chamber for circulating cooling fluid and a pump for supply of additional cooling fluid to be mixed with the circulating cooling fluid, the combination of an outlet from said mixing chamber for surplus cooling fluid, an inlet in said mixing chamber for the additional cooling fluid, baffle means in said mixing chamber situated between said outlet and said inlet, a tubular chamber disposed below said baffle means, said tubular chamber consisting of a horizontal cylindric chamber, one end of which being open to a channel directed tangentially to said horizontal chamber to cause the circulating cooling fluid to pass therethrough.
7. In a cooling system for combustion engines comprising a cylinder cooling jacket and a mixing chamber for circulating cooling fluid and a pump for supply of additional cooling fluid to be mixed with the circulating cooling fluid, the combination of an outlet from said mixing chamber for surplus cooling fluid, an inlet in said mixing chamber for the additional cooling fluid, baffle means situated in said mixing chamber between said outlet and said inlet, a cylindric chamber disposed below said baffle means, a tubular baffle arranged coaxially in said cylindric chamber, a radial passage in said tubular baffle, said baffle and said passage being adapted to receive and guide a portion of the circulating cooling fluid escaping from said cylinder cooling jacket.
8. In a cooling system for combustion engines comprising a cylinder cooling jacket and a mixing chamber for circulating cooling fluid and a pump for supply of additional cooling fluid to be mixed with the circulating cooling fluid, the combination of an outlet from said mixing chamber for surplus cooling fluid, an inlet in said mixing chamber for the additional cooling fluid, baffle means in said mixing chamber situated between said outlet and said inlet, a cylindric chamber disposed below said baffle means, a tubular baffle coaxially and rotatably arranged in relation to said cylindric chamber, a radial passage in said tubular baffle and a surface of said cylindric chamber adapted to cooperate with the mouth of said radial passage to increase or decrease the area thereof in turning said tubular baffle.
9. In a cooling system for combustion engines comprising a cylinder cooling jacket and a mixing chamber for circulating cooling fluid and a pump for supply of additional cooling fluid to be mixed with the circulating cooling fluid, the combination of an outlet from said mixing chamber for surplus cooling fluid, an inlet in said mixing chamber for the additional cooling fluid, baffle means in said mixing chamber situated between said outlet and said inlet, a cylindric chamber disposed below said baffle means, one end of said cylindric chamber provided with helical guide surface associated with an axial surface, said inlet for the additional cooling fluid tangentially arranged with the wall of said cylindric chamber and situated adjacent to said one end of said cylindric chamber, a tubular baffle with radial passage arranged coaxially in said cylindric chamber, and a helical guide vane surrounding said tubular baffle.

GUSTAF WALDEMAR BJÖRKSTRÖM.
